M. WENZEL

APPARATUS FOR WITHDRAWING AIR FROM SUCTION BOXES

Filed July 7, 1928

Max Wenzel,
Inventor.
Delos V. Hayes,
Attorney.

UNITED STATES PATENT OFFICE.

MAX WENZEL, OF MULDENSTEIN, NEAR BITTERFELD, GERMANY.

APPARATUS FOR WITHDRAWING AIR FROM SUCTION BOXES.

Application filed July 7, 1928, Serial No. 290,938, and in Germany October 29, 1926.

This invention relates to apparatus for withdrawing air from suction boxes, and with regard to certain more specific features to said apparatus to be used in connection with suction boxes for paper machines and the like.

Among the several objects of the invention may be noted the provision of a more economical and less cumbersome means for effecting an abstraction of air or the like from a series of suction chambers adapted to be operated at different pressures. Other objects will be in part obvious and in part pointed out hereinafter.

The invention accordingly comprises the elements and combinations of elements, steps and sequence of steps, features of construction, and arrangements of parts which will be exemplified in the structure hereinafter described, and the scope of the application of which will be indicated in the following claims.

In the accompanying drawing, in which is illustrated one of various possible embodiments of the invention, the single figure illustrates the improved apparatus.

The general type of paper machine suction boxes to which this invention applies are known in the art, and an example of such a suction box is disclosed in my United States Patent 1,518,116, issued December 2, 1924. Another example is disclosed in my German Patent 401,935, issued September 15, 1924. It is to be understood that the invention applies to boxes wherein a plurality of rolls are served by one box, as shown in said patents, and a new and improved type wherein each roll is served by one box, as disclosed in my co-pending United States patent application entitled Roll suction device, filed of even date (file 3121). The invention can also be used on flat and other types of suction boxes.

It is customary to operate these suction boxes of paper machines (for eliminating water from cellulose and the like) at partial vacuums of various degrees. This is usually done by increasing the partial vacuum from suction box to suction box in accordance with the progressive elimination of water from the web of paper passing over successive boxes on roll-supported conveyor wire or the like. Up until the present time these various degrees of negative pressure in the suction boxes were induced by causing an air pump to produce a partial vacuum required, for instance in the last suction box, while the negative

pressures of lower value in the other suction boxes were decreased by throttling. Sometimes a plurality of generators of this negative pressure were utilized, thereby producing various negative pressures corresponding to the steps of partial vacuum desired for the suction boxes. It will be understood that both of these methods are not economical and are cumbersome.

The present improved method avoids the defects set out above, there being employed a centrifugal suction pump having a plurality of stages of pressure, these pumps in general being known. They are sometimes referred to as multi-stage vacuum pumps. The various degrees of vacuum of this class of centrifugal pump are adapted in regard to their number, the value of the negative pressure and the air efficiency, to the negative pressures and volumes of air required at the various suction devices or groups of suction devices, and each one of the various stages of the blower or pump is provided with a suction pipe. By a tubular connection between each suction pipe of the various stages of the blower and the corresponding suction boxes or groups of suction boxes, the combinations for the operation in accordance with the new method are provided.

The figure shows an embodiment of a plant illustrating in side elevation a movable longitudinal sieve or netting 1 which moves preferably in the direction shown by vector 3. Letters a_1, a_2, a_3, a_4 indicate the suction boxes, letters b_1, b_2, b_3, b_4 the communicating conduits leading to the blower or suction device, where said conduits connect to the suction pipes of the various stages of the blower d , as indicated at d_1, d_2, d_3, d_4 . Letter d_0 indicates the final stage of the blower having the exhaust b_0 . Letter e represents the driving motor of the blower d and c_1, c_2, c_3, c_4 indicate the water discharge pipes of the suction boxes for draining off water sucked out of the paper passing over the boxes on the netting 1.

The operation is as follows:

The negative or subatmospheric pressures of the various blower stages, chambers or steps connected with suction pipes d_1, d_2, d_3, d_4 are slightly higher than the maximum negative pressure required in the corresponding suction boxes a_1, a_2, a_3, a_4 in order to compensate for the losses of pressure in the communicating conduits.

The pump then extracts the air from the

suction boxes. The extracted water flows into the pipes c_1 , c_2 , c_3 , c_4 and to a sump 5. The chamber, stage or step d_4 of the blower draws the highest negative pressure, because, among other things, it has the lowest back pressure, the other stages sucking air therefrom in series. Stage d_4 sucks air from box a_4 and exhausts to stage d_3 . Stage d_3 draws air from box a_3 and from stage d_4 and exhausts to stage d_2 and so on, until stage d_0 , which takes the exhaust of stage d_1 , itself exhausts into the atmosphere. The stage d_4 , therefore, is connected with the last suction box a_4 requiring the best vacuum. As stated, the stage d_3 receives the air drawn in by suction by the stage d_4 , compresses this air to the next negative pressure and withdraws air corresponding to this negative pressure from the suction box a_3 . The other stages operate accordingly, the last stage d_0 exhausting this air from the various blower chambers or steps d_1 , d_2 , d_3 , d_4 , at atmospheric pressure, so that this air may be discharged into the atmosphere through the conduit (b_0). Clearly a plurality of suction boxes may be connected with any step or chamber of the blower. A variation of the output as to volume and as to pressure is made feasible by varying the number of revolutions of the blower or by throttling respectively the ultimate discharge pipe b_0 as by a valve 7 or by throttling the suction conduits of the various steps or chambers as by valves 9, 10, 11, 12. In general, however, this last-named variation is required within relatively narrow limits only, inasmuch as the basic variations of the various partial vacuums are furnished by the multi-stage action of the blower itself, which steps are adapted to the operation of the paper machine to which the device is connected.

It is to be understood that the present invention is not limited to multi-stage centrifugal suction apparatus but may employ any multi-stage class of pump, such as a multi-stage reciprocating pump or others. The multi-stage action permits one pump to be used for various degrees of suction, without excessive throttling and eliminates the use of an excessive number of suction machines each operating to compress to atmospheric pressure.

For instance, it will be seen that in my apparatus stage d_4 , which draws the best vacuum needs only compress up to the sub-atmospheric pressure of stage d_3 into which it exhausts and so on, the last stage d_0 which must pump to atmosphere sucking a more moderate vacuum.

This invention, among other things, effects what is known as a bleeding action from each of various chambers to be evacuated to each of various stages of compression in a multi-stage evacuating pump.

It will be seen that all the vacuums may be varied at once by varying the revolutions of the single pump d and this is also a feature intended to be covered hereby.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. Suction apparatus for paper machines comprising in combination, suction boxes, a multi-stage vacuum pump and means communicating between separate stages of the pump and separate suction boxes.

2. Suction apparatus for paper machines comprising in combination, suction boxes, a multi-stage centrifugal vacuum pump and means communicating between separate stages of the pump and separate suction boxes.

3. Suction apparatus for paper machines comprising in combination, suction boxes, a multi-stage vacuum pump, means communicating between separate stages of the pump and separate suction boxes, a discharge for said pump for effecting discharge from several stages and means for throttling said discharge whereby subatmospheric pressures within said boxes may be varied.

4. Suction apparatus for paper machines comprising in combination, suction boxes, a multi-stage vacuum pump, means communicating between separate stages of the pump and separate suction boxes, said pump being adapted to have its rate of action varied.

5. Suction apparatus for paper machines comprising in combination, suction boxes, a multi-stage centrifugal vacuum pump, means communicating between separate stages of the pump and separate suction boxes, said pump being adapted to have its rate of rotation varied.

In testimony whereof, I have signed my name to this specification this 8th day of June, 1928.

MAX WENZEL.
